UNITED STATES PATENT OFFICE.

ALOIS P. SWOBODA, OF NEW YORK, N. Y.

PROJECTILE.

1,231,451.

Specification of Letters Patent. Patented June 26, 1917.

Application filed May 2, 1916. Serial No. 94,955.

To all whom it may concern:

Be it known that I, Alois P. SWOBODA, a citizen of the United States, residing at New York, in the county of New York, State of New York, have invented a new and useful Projectile; and I do hereby declare the following to be a full, clear, and exact description of the invention, such as will enable others skilled in the art to which it applies to make and use the same.

The present invention relates to certain new and useful improvements in projectiles, and has for its object to provide a device of this character which embodies novel features of construction whereby a charge of some highly inflammable substance can be carried by the projectile and automatically ignited and scattered upon the object struck by the projectile.

Further objects of the invention are to provide a projectile of this character which is comparatively simple and inexpensive in its construction, which can be fired from the ordinary guns without necessitating any changes therein, which may or may not carry an explosive charge in addition to the inflammable substance, and which can be handled with safety.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:—

Figure 1 is a longitudinal sectional view through a cartridge loaded with a projectile constructed in accordance with the invention.

Fig. 2 is a similar view showing a modified form of the invention.

Fig. 3 is a detail longitudinal sectional view through the outer end of the inflammable substance receiving chamber, showing the details of the valve connecting the inflammable substance chamber and the expansion pocket.

Fig. 4 is a plan view of the valve casing before the same is formed into a tube.

Corresponding and like parts are referred to in the following description and indicated in all the views of the drawings by the same reference characters.

Referring to the drawings, which illustrate one possible embodiment of the invention, the numeral 1 designates the body of a projectile which has the base thereof fitted within the mouth of a cartridge shell 2, said shell containing the usual powder charge 3, and having a primer or ignition cap 4 in the head thereof. The nose of the projectile 1 is tapered, as indicated at 1^a, and has a comparatively fragile chamber 5 fitted thereon, said chamber being adapted to be filled with some highly inflammable liquid or substance, such as the gasoline 6, and having an expansion pocket 7 in one end thereof to provide for the expansion and contraction of the inflammable substance which will be incident to the changes of temperature therein. The shell 5 is preferably cylindrical in shape, and the diameter of the shell is considerably less than that of the body portion 1 of the projectile or of the caliber of the gun from which the projectile is to be fired. This chamber 5 will be fitted upon the nose of the projectile in such a manner that the chamber and projectile are coaxial and, owing to the smaller diameter of the chamber 5, the walls thereof will not come into contact with the bore of the gun, thereby preventing the chamber and the contents thereof from becoming unnecessarily heated by friction and eliminating any possibility of the walls of the chamber 5 being bent or ruptured by the discharge of the projectile from the gun.

When the projectile strikes against some object, the chamber 5 will be shattered or crushed, thereby causing the charge 6 of inflammable substance to be scattered and some means, such as the ignition cap 8, is provided for setting fire to the substance 6 at the same time that it is scattered. The damage which will ordinarily be done by the projectile 1 is thus augmented by the damage which may be done by the burning of the scattered inflammable substance 6. There is thus not only the smashing effect of the projectile to be contended with, but also the possibility of a serious fire or conflagration being brought about by the burning of the inflammable substance which is scattered in all directions when the walls of the chamber 5 are shattered by the impact of the projectile against some object. In a naval engagement there would be the possibility of setting fire to the ship of the enemy, as well as that of destroying the ship by the impact.

or explosion of the projectile itself. The use of the projectile is not by any means to be restricted to naval warfare, however, since it can be used for the purpose of clearing out 5 trenches, breaking down walls, or for any kind of fighting.

The extremity of the chamber 5 is preferably pointed, as indicated at 5^a, so as to reduce the resistance of the air to the flight 10 of the projectile, and the expansion pocket 7 may be conveniently located in the pointed end of the chamber. A transverse partition 9 separates the expansion pocket 7 from the interior of the body portion of the chamber 5, said partition carrying a double acting 15 valve 10 which is constructed to admit of a back and forth movement of the inflammable liquid between the chamber 5 and the expansion pocket 7. This valve 10 may 20 be of any suitable construction, and may be mounted in any suitable manner, although for the purpose of illustration it is shown as arranged within a tubular member 11 which extends through the partition and 25 interposed between a pair of springs 12 which bear at their outer ends against flanges 13 projecting inwardly from the extremities of the tubular member. The end portions of the tubular member 11, projecting 30 upon opposite sides of the partition 9, are provided with the respective longitudinal slots 14, so that when the valve 10 is moved in either direction communication is established between the chamber 5 and the 35 expansion pocket 7, although when the valve is in an intermediate position the expansion pocket is cut off from the chamber 5. The chamber 5 will be heated by the discharge of the projectile and the rapid passage 40 thereof through the air, and this will cause the inflammable substance 6 to become heated and expand, although this expansion is taken care of by the pocket 7.

A suitable opening 15 would be provided 45 in the chamber 5, preferably at one side thereof, for enabling the chamber to be readily filled with the inflammable substance 6. This opening could be closed in any suitable manner, as by means of a plug 50 16, which is adapted to be screwed tightly into position therein. This plug should leave the exterior of the chamber as smooth as possible in order that there may be no unnecessary air resistance.

The chamber 5 may be fitted upon the 55 nose of the projectile 1 in any suitable manner. In the present instance the inner end of the chamber 5 telescopes upon and has a threaded engagement with a reduced cylindrical head 1^b at the extremity of the nose 1^a of the projectile 1. The rear end of the 60 chamber 5 may be provided with an interior flange 17, and a washer or packing ring 18 may be interposed between this flange and 65 the end of the projectile, thereby insuring

a perfectly tight joint which will prevent the leakage of the inflammable liquid 6.

A slight modification is shown by Fig. 2, in which the chamber 5 is shown as applied to the end of an explosive projectile 1^x. This projectile is filled with an explosive charge 19, and any conventional means, such as a cap or fuse, may be provided for discharging the explosive charge 19 at the proper time. The chamber 5 containing the 75 inflammable substance would be simultaneously shattered, and the inflammable substance ignited by the explosion of the projectile. The chamber 5 may thus be applied to either an explosive or a non-explosive projectile, or to any kind of a base for carrying the same, and the destructiveness of any projectile to which it may be applied is greatly increased.

Having thus described the invention, 85 what I claim as new and desire to secure by Letters Patent, is:—

1. A projectile including a body having a contracted nose at one end thereof, a chamber having a smaller diameter than the body and fitted upon the contracted nose thereof, the chamber and body being co-axial so that the walls of the chamber will not contact with the bore of the gun, a quantity of inflammable material packed within 95 the chamber and adapted to be scattered when the chamber is broken by the impact of the projectile with an object, and means for igniting the inflammable material as it is scattered.

2. A projectile including a body having a contracted nose at one end thereof, a chamber having a smaller diameter than the body and formed with an open end which is telescoped upon the contracted 105 nose of the body, the chamber and base being co-axial so that the walls of the chamber will not contact with the bore of the gun, an internal flange within the chamber adjacent to the open end thereof, a packing ring interposed between the internal flange and the body to insure a tight joint, a quantity of inflammable material housed within the chamber and adapted to be scattered when the chamber is shattered by impact of the projectile with an object, and means for igniting the inflammable material as it is scattered.

3. A projectile including a body, a chamber fitted upon one end of the body and having a smaller diameter than the same, the chamber and body being co-axial so that the walls of the chamber will not contact with the bore of the gun, a quantity of inflammable liquid housed within the chamber and adapted to be scattered when the chamber is shattered by impact of the projectile with an object, a partition providing an expansion pocket within the chamber, valved means for permitting portions 120 125 130

of the inflammable liquid to enter and leave the expansion pocket as the inflammable liquid expands and contracts due to changes in temperature, and means for igniting the inflammable material as it is scattered.

4. A projectile including a body, a chamber fitted upon the body and containing an inflammable substance adapted to be scattered when the chamber breaks, a partition ¹⁰ providing an expansion pocket within the chamber, valved means permitting portions of the inflammable substance to enter and

leave the expansion pocket as the inflammable substance expands and contracts due to changes in temperature, and means for igniting the inflammable material as it is scattered. ¹⁵

In testimony whereof I have signed my name to this specification in the presence of two subscribing witnesses.

A. P. SWOBODA.
